UNITED STATES PATENT OFFICE.

WILLIAM M. FORTESCUE, OF LEAVENWORTH, KANSAS.

DESIGN FOR A DARNING-SPOOL.

SPECIFICATION forming part of Design No. 33,940, dated January 22, 1901.

Application filed December 24, 1900. Serial No. 40,983. Term of patent 14 years.

To all whom it may concern:

Be it known that I, WILLIAM M. FORTESCUE, a citizen of the United States, residing at Leavenworth, in the county of Leavenworth 5 and State of Kansas, have produced a new and original Design for a Darning-Spool, of which the following is a specification.

This invention relates to a new and original design for a darning-spool, and has for 10 its object to provide a design of this character which shall be both useful and ornamental.

The invention consists in the design hereinafter described, and shown in the drawings.

In the drawings, Figure 1 is a side elevation 15 of a darning-spool embodying the herein-described design. Figs. 2 and 3 are elevations of the respective ends thereof.

Like characters of reference designate corresponding parts in all the figures of the drawings.

Referring to the drawings, 1 designates the body of the darning-spool, which is in the form 20 of a bulb, having an outer rounded blunt end, which is free from projections, and a spool-shaped cylindrical shank 2 at the inner end 25 of the body. The inner end portion of the body is tapered toward the shank portion more gradually than the blunt outer end and gives the body an elongated appearance with

a general taper inwardly from the outer to 30 the inner ends thereof. The cylindrical shank or spool portion 2 has opposite terminal and marginal circular flanges 3 and 4, which have their inner faces 5 and 6 respectively beveled inwardly to the cylindrical surface of the 35 shank. The outer flange 3 is flush with the outer flat circular face of the shank, which has a central circular opening 7 therein. The inner flange 4 lies at the intersection of the shank and the body and is slightly greater in 40 diameter than the adjacent inner end of the body, while the outer face of the flange is flat, free from projections, and forms an annular shoulder at the inner end of the body. Both flanges are of the same diameter and have flat 45 outer marginal edges of equal widths. The outer end of the bulb-shaped body has a central circular opening 8.

What is claimed is—

The design for a darning-spool herein shown 50 and described.

In testimony that I claim the foregoing as my own I have hereto affixed my signature in the presence of two witnesses.

WILLIAM M. FORTESCUE.
